US00D749581S

(12) **United States Design Patent**
Olsson et al.

(10) **Patent No.:** **US D749,581 S**
(45) **Date of Patent:** **** Feb. 16, 2016**

(54) **GLASSES FRAME**

(71) Applicant: **Google Inc.**, Mountain View, CA (US)

(72) Inventors: **Maj Isabelle Olsson**, San Francisco, CA (US); **Matthew Wyatt Martin**, Ross, CA (US)

(73) Assignee: **Google Inc.**, Mountain View, CA (US)

(**) Term: **15 Years**

(21) Appl. No.: **29/535,126**

(22) Filed: **Aug. 4, 2015**

Related U.S. Application Data

(57) **CLAIM**

The ornamental design for a glasses frame, as shown and described.

DESCRIPTION

FIG. 1 is a front perspective view of a glasses frame according to our design;

FIG. 2 is a front elevation view of the glasses frame of FIG. 1; FIG. 3 is a back elevation view of the glasses frame of FIG. 1; FIG. 4 is a left elevation view of the glasses frame of FIG. 1; FIG. 5 is a right elevation view of the glasses frame of FIG. 1; FIG. 6 is a top elevation view of the glasses frame of FIG. 1; and,

FIG. 7 is a bottom elevation view of the glasses frame of FIG. 1.

Broken lines are environmental only and form no part of the claimed design.

The lenses shown in the figures are presented with an exemplary thickness and curvature. The thickness and curvature of the lenses is not part of the claimed design.

1 Claim, 3 Drawing Sheets
